GANG RELAY SWITCH ARRANGEMENT

Albert F. Horlacher, Palatine, Ill., assignor to
 C. P. Clare & Company, Chicago, Ill., a corporation of Illinois

Application November 26, 1945, Serial No. 630,807

4 Claims. (Cl. 200—1)

1

The present invention relates to gang relays wherein a single armature bar is utilized to operate a multiplicity of armature springs to make or break contact with groups of stationary make or break springs. In devices of this character the fact that there are so many springs makes it difficult to obtain accurate alignment and spacing of the springs and contacts carried thereby. In these relays difficulty is also encountered due to vibration of the springs particularly the make or break springs.

It is the principal purpose of my invention to provide a gang relay assembly of such nature that the several make or break springs are correctly spaced and aligned and the armature springs are moved in unison equal amounts for each spring in order that proper contact is assured throughout the assembly.

It is also a purpose of this invention to provide a novel gang relay assembly which facilitates the mounting of the several springs and eliminates the necessity for jigs and the like to establish proper spacing.

A further purpose of the invention is the provision of a novel actuator unit by which the movement of the relay armature is transmitted uniformly to the several armature springs, the actuator units being independent for each vertical bank of springs so that if desired they can be removed and applied without disturbing the mounting of the springs themselves.

It is also a purpose of my invention to provide a spring assembly for gang relays of the character described wherein vibration of the individual springs is substantially eliminated by connecting the several make or break springs in transverse banks and by inter-connecting the armature springs in a direction at right angles to the interconnection of the make or break springs so as to reduce any tendency on the part of the armature springs to vibrate.

The nature and advantages of my invention will appear more fully from the following description and the accompanying drawings wherein a preferred form of the invention is shown. It should be understood, however, that the drawings and description are illustrative only, and are not to be taken as limiting the invention except insofar as it is limited by the claims.

In the drawings:

Figure 1 is a plan view of a gang relay assembly embodying my invention;

Figure 2 is a view in side elevation of the assembly;

Figure 3 is a fragmentary sectional view taken

2

on the line 3—3 of Figure 1 and illustrating the spring assembly;

Figure 4 is a detailed view of one of the armature springs this view being taken from line 4—4 of Figure 3;

Figure 5 is a fragmentary sectional view taken on the line 5—5 of Figure 3;

Figure 6 is a fragmentary sectional view taken on the line 6—6 of Figure 3 and on an enlarged scale, and;

Figure 7 is a side view of the spacer element employed in spacing the armature springs.

Referring now to the drawings, the gang relay is made up with a heel piece 10 which forms the mounting for one or more relay coils 11 which are wound upon cores 12 having spool ends 13 and 14 rigidly secured thereto. The heel piece 10 has the cores 12 secured thereto by screws 15. In addition the spool heads 13 have wiring terminal projections 16 that engage the down turned end 17 of the heel piece to aid in securing the relay core and coil in place. There are two of the projections 16 on each head 13 and each projection has a coil terminal 18 projecting therefrom.

25 The relay armature 19 is mounted on the front end of the heel piece 10 by screws 20 that are threaded into the heel piece at an angle of 45°. These screws pass through slots 21 and 22 in the armature. Springs 23 are wound on the screws 20 and press washers 24 against the angle at the corner of the armature so as to force the interior corner of the armature against the edge 25 at the forward end of the heel piece. The heel piece is beveled as indicated at 26 so that the armature 30 can rock on the edge 25. The armature extends down across the end of the core 12 and is provided with a spacing screw 27 by which its stroke can be adjusted. On top of the heel piece 10 the armature has two side bars 28 and 29 projecting over the heel piece and parallel thereto, the side bars being connected by a cross bar 30 which is adapted to engage a plurality of armature spring actuators 31 which will be described in detail hereinafter.

45 A mounting plate 32 is fastened on the heel piece 10 by suitable screws 33. This mounting plate is threaded to receive a series of screws 34 which are utilized to secure the banks of make or break contact springs 35 and armature springs 36. The construction of the banks of make or break springs is such that they provide the means also for mounting the armature springs in place.

Each make or break contact spring comprises a wiring terminal portion (see Figure 3) 37, a mounting portion 38 which is provided with

spaced apertures to receive the screws 34, an intermediate spring portion 39 and a bifurcated front end portion 40. The portion 40 has two arms 41 and 42 each of which carry a contact 43.

The armature spring 36 is substantially a duplicate of the make or break contact spring having the wiring terminal 44 the apertured mounting portion 45 and intermediate spring portion 46, and a bifurcated portion 47, the two arms 48 and 49 of which carry contacts 50. The armature springs however, in addition to the parts just described, have tongues 51 between the arms 48 and 49, and these tongues have down turned tips 52 for cooperation with the actuators 31.

The several make or break contact springs 35 are secured together in banks by molding them in two bars 53 and 54, of a suitable molding compound such as the synthetic resin sold under the name Bakelite. The bar 53 covers the apertured portion 38 of the spring 35 while the bar 54 is located near the bifurcated portion 40 of the spring 35. The bars 53 are so constructed as to nest by providing sockets at 55 and projections at 56 around the screws 34. The bars are, of course, provided with suitable apertures to receive the screws 34. When a plurality of the bars 53 are stacked one upon the other the projections 56 nest in the recesses 55. The armature springs 36 have their apertures 57 of such size as to fit over the projections 56 so that these projections serve to align the armature springs and hold them in place when the parts are assembled.

The bars 54 are recessed on their sides as indicated at 58 (see Figure 6) so that the armature springs may have room to move up and down a sufficient amount to permit the contacts 50 thereon to engage and separate from the contacts 43 on the springs 35. The bars 54 since they connect the several springs 35 of a bank prevent individual vibration of any one of the springs 35 and furthermore they align all of the springs at a point near to the contact ends thereof, thus making it possible to have very accurate control of the alignment of the contacts 43. The bifurcation of the springs 35 provides two spaced apart contact making portions, which is of advantage in making sure that good contact will be obtained at all times. The smaller contacts that can be used in this fashion will always engage on at least one of the arms 41-42 with the corresponding contacts of the armature spring even though a small particle of dust might temporarily get caught on one of the contacts.

The armature springs 36 are of course aligned at the rear ends and spaced by the bars 53. Near their contact points, these armature springs are connected so as to move together by means of the actuator 31. The actuator 31 consists of a bar of insulation having a series of spaced apertures 59 through which the tongues 51 can be extended. The apertures are enlarged at 60 to facilitate threading the tongues in the actuator bars. The openings 59 are large enough to permit the actuator to be snapped off of the tongues and replaced very readily. The mode of replacement comprises moving the actuator bar down in front of the tongues until the top opening of the bar will receive the top tongue 51 in a vertical row of the springs. Then by pressing upwardly and inwardly on the lower end of the actuator bar it can be lifted above the level of the bar 30 carried by the armature and shoved inwardly forcing all of the tongues through the bar 31 so that their down turned ends 52 can project downwardly at

the small end of the opening 51. The spring tension will then keep the bars in place while the relay is operated.

It is believed that the construction and assembly of the gang relay embodying my invention will be clear from the foregoing description. It will be noted that by means of this construction the make or break contact springs are uniformly lined so that when stacked one upon the other by means of the bars 53 they may be clamped in place by the screws 34 so as to retain substantially uniform spacing throughout several levels. The bars 54 insure alignment of the several springs of a bank and furthermore prevent individual spring vibration which is harmful. In assembling the parts the armature springs 36 are readily aligned by means of the projections 56 on the bars 53, and when the actuator bars 31 are applied the front or contact carrying ends of the armature springs are properly spaced. The bars 31 are of such length that when they rest upon the cross bar 30 the armature springs are slightly tensioned so that all of the tongues 51 press downwardly against the lower walls of the apertures 59. This construction tends to eliminate any armature spring vibration, the result being a gang relay assembly wherein the contacts are accurately spaced, and individual armature spring and make or break spring vibration is practically eliminated.

Having thus described my invention I claim:

1. In a switch of the character described, a spring assembly comprising rows of stationary springs having free end portions provided with contacts, and rows of movable springs having end portions provided with contacts for engagement with said first named contacts, a mounting bar of insulation carrying each row of stationary springs in spaced relation and in which a portion of each stationary spring, remote from the contacts thereon, is fixed, cooperating projections and recesses on opposite sides of the mounting bars for aligning them, said movable springs having apertures receiving the projections whereby the movable springs may be interposed between and held by two adjacent mounting bars, the free ends of the movable springs being interconnected in rows transverse to the rows of stationary springs by insulating bars and means securing the mounting bars together.

2. In a switch of the character described, a spring assembly comprising rows of stationary springs having free end portions provided with contacts, and rows of movable springs having end portions provided with contacts for engagement with said first named contacts, a mounting bar of insulation carrying each row of stationary springs in spaced relation and in which a portion of each stationary spring, remote from the contacts thereon, is fixed, a second bar of insulation interconnecting and securing the several stationary springs of a row together, said second bar being intermediate the first bar and the contacts of said springs, and means securing the mounting bars together, the rows of movable springs being interposed between and secured by the mounting bars in alignment with the stationary springs, the free ends of the movable springs being interconnected in rows transverse to the rows of stationary springs by insulating bars.

3. In a switch of the character described, a spring assembly comprising rows of stationary springs having free end portions provided with contacts, and rows of movable springs having end portions provided with contacts for engagement

with said first named contacts, a mounting bar of insulation carrying each row of stationary springs in spaced relation, and in which a portion of each stationary spring, remote from the contacts thereon, is fixed, the rows of movable springs being interposed between and secured by the mounting bars in alignment with the stationary springs, the springs having bifurcated contact carrying ends, each bifurcation having a contact thereon, and actuator bars extending between the bifurcations, said bars having spaced apertures therein, and the movable springs having tongues extending through the apertures and bent over to hold the actuator bars in place.

4. In a switch of the character described, a spring assembly comprising rows of stationary springs having free end portions provided with contacts, and rows of movable springs having end portions provided with contacts for engagement with said first named contacts, a mounting bar of insulation carrying each row of stationary springs in spaced relation, and in which a portion of each stationary spring, remote from the contacts thereon, is fixed, the rows of movable springs being interposed between and secured by the mounting bars in alignment with the stationary springs, the springs having bifurcated contact
